SHOOTING RANGE

Edward A. Gorney, Holly, Mich., assignor to Rose A. Gorney, Holly, Mich., and Richard F. Gibbs and M. J. Gilbert, both of Flint, Mich.

Application May 25, 1937, Serial No. 144,677

4 Claims. (Cl. 273—101)

My invention relates to a new and useful improvement in a shooting range adapted for use in target practice shooting and has as its object the provision of a construction whereby, target practice may be effectively carried on and the one practicing readily apprised of the results of the shots.

Another object of the invention is the provision of a target practice construction having a lighting system for illuminating the target for a predetermined length of time and automatically shutting off upon the elapse of the predetermined amount of time.

Another object of the invention is the provision of a target practice construction so arranged that a target may be illuminated and set into motion simultaneously for a limited period of time thus requiring the operator to manifest skill and speed in shooting.

Another object of the invention is the provision of a coin controlled mechanism for controlling the operation of the structure.

Another object of the invention is the provision of a coin controlled means for releasing a predetermined number of bullets at each operation.

Another object of the invention is the provision in a construction of this kind, of a bullet dispensing mechanism capable of maximum capacity and easily and quickly operated to release a predetermined number of bullets at each operation.

Another object of the invention is the provision in a construction of this kind, of means for electrically indicating the results of each shot.

Another object of the invention is the provision of a construction in which a gun shall be mounted in such a manner that it can not be removed from the enclosure leading to the target itself.

Another object of the invention is the provision of means for indicating the number of operations of the device.

Another object of the invention is the provision of a device of this class which will be simple in structure, economical of manufacture, durable, highly efficient in use, easily operated, compact and safe.

Other objects will appear hereinafter.

The invention consists in the combination and arrangement of parts hereinafter described and claimed.

The invention will be best understood by a ref-

erence to the accompanying drawings which form a part of this specification, and in which,

Fig. 1 is a side elevational view of the invention with a part broken away and a part shown in section.

Fig. 2 is a front elevational view of the invention.

Fig. 3 is a longitudinal, central, vertical, sectional view of the upper part of the invention.

Fig. 4 is a view taken on line 4—4 of Fig. 3. 10

Fig. 5 is a view taken on line 5—5 of Fig. 3.

Fig. 6 is a view taken on line 6—6 of Fig. 1.

Fig. 7 is a view taken on line 7—7 of Fig. 6.

Fig. 8 is an enlarged fragmentary view of the feeding magazine with parts broken away and 15 parts shown in section.

Fig. 9 is a view taken on line 9—9 of Fig. 7 with parts broken away and parts shown in section.

Fig. 10 is a fragmentary side elevational view 20 of the upper part of the feeding magazine.

Fig. 11 is a view taken on line 11—11 of Fig. 5.

Fig. 12 is a fragmentary view taken on line 12—12 of Fig. 11.

Fig. 13 is a fragmentary view taken on line 25 13—13 of Fig. 11.

Fig. 14 is a diagrammatical view illustrating the wiring used in the invention.

Fig. 15 is a view similar to Fig. 5 showing a modified form of the invention.

30

Fig. 16 is a view taken on line 16—16 of Fig. 15.

In the form illustrated, the invention is indicated as a mechanism which is operated upon the pressing inwardly of a plunger, the pressing inwardly of which would be resisted until the 35 deposit of a coin in the required position. While this illustration has been made it will, it is believed, appear obvious as the description proceeds that the coin release of the inwardly pressible plunger may be dispensed with, if desired. 40 The construction is one which is very compact and may be positioned in a small space so that the target range provided in this invention may be set up in a recreation room, restaurant, store or the like.

45 The invention comprises a base 36 mounted upon and projecting upwardly from which is an enclosing housing embodying the side walls 37 and 38, the front 39, the top 42, and the rear wall 43, extending rearwardly on the base 36 and 50 projecting upwardly therefrom in spaced relation are the supporting standard or wall 40 and 41. These standards or walls 40 and 41 serve as a support for the rearwardly extended cylindrical housing or hollow shell 44, which is suitably se- 55

cured, as by welding, to the rear wall 43. At the rear end of this housing 44 is a closure 45 swingably attached thereto as at 46 and provided with a suitable locking mechanism 47. An opening 48 is formed in the front wall 39 and mounted on the front wall so as to surround this opening 48 and extending inwardly therefrom is the tube or drum 49 secured within which, by means of the chain 51, is a gun 50 preferably of the rifle type. The connection of the gun 50 with the tube 49 is such that the muzzle of the gun can not be withdrawn from the tube 49 and since it is preferred to form the tube 49 from metal, it is obvious that an accidental discharge of the gun 50 would necessarily be within the tube 49 and directed toward the rear end thereof. This tube 49 is slightly telescoped with the conical deflecting tube 52 which is slightly larger at its large end than the tube 49 and which is mounted in spaced relation by the spacing chairs 53 which may be secured in any desired manner to either of these tubes, but preferably to the tube 52. The front or outer end of the tube 52 is secured by welding, or in any other suitable manner, to the lugs 54 which project downwardly from the cut-away portion of the rear wall 43. The rear or inner end of the tube 52 projects inwardly of the conical tube 55 and is mounted in spaced relation thereto by the spacing chair 53". The front or outer end of the tube 55 is supported by the supporting chair 53' mounted within the housing 44. The rear or inner end of the tube 55 is provided with a lug 57 which is pivotally connected by the pin 58 to the standard 56 which projects upwardly from the bottom of the housing 44. Positioned within the housing, at the forward end of the device and preferably at the upper side thereof, is the compartment housing 59 divided into a plurality of compartments 60, 61, and 62 each of which is again subdivided into separate compartments communicating with which is an opening formed in the front wall 39 and closed by a lens 63. In each of these compartments is mounted a socket 64 in which a light bulb 64' is threaded. The wires leading to these light bulbs are passed through the cable 65 which leads into the control or switch box 73. A bracket 66 serves to support a light bulb socket 67 and a light bulb socket 69 is mounted on the floor plate 68. This floor plate 68, as well as the top plate 42 is provided with the ventilating openings 70.

Mounted within the housing or tube 44 is a bracket 71 which serves to support a light socket 72. Depending from adjacent the rear end of the tube 44 is a pair of spaced supporting arms 74 and 75 each of which is provided at its lower end with a bearing 76 in which the shaft 77 is rotatably mounted. Pivotally mounted on the shaft 77 (see Fig. 11) is a sleeve 78 projecting outwardly from which is an arm 79. This arm 79, as shown in Fig. 5, is connected at its end pivotally to one end of a link 80, the other end of which is pivotally connected eccentrically to the disc 81 which is fixedly mounted on the shaft 82 projecting outwardly from the gear box 83 and which is rotated by the electric motor 84. Mounted on the shaft 85 of this motor is a fan 86 which serves to expel the air and gas from the interior of the tube 44 through the screen 86'. A bracket 87 is mounted in the tube 44 for supporting the motor 84.

Mounted on the shaft 77, as shown in Fig. 11, is a plate 88 which is positioned at one side of the sleeve 78. Mounted on this shaft 77 at the op-

posite side of the sleeve 78 is a plate 89 which is connected to the plate 88 by the stay bolt 90 which passes through each of the plates 89 and 88 and also through the sleeve 78. Consequently, it is obvious that upon a rocking of the sleeve 78, the plates 88 and 89 are rocked in unison therewith.

Formed in the plate 88 is an opening 91 in which is adapted to slideably engage an annular target forming member 92 having at its inner 10 end a radially projecting peripheral flange 93 of larger outside diameter than the diameter of the opening 91 so as to overlie the same. The member 92 is of an outside diameter less than the diameter of the opening 91 so that there is, extending around the member 92, a space between the member 92 and the plate 88 sufficiently large to permit the passage of a bullet therethrough. Should a bullet strike this space it will pass between the members 92 and 88 and pass rearwardly until it strikes the flange 93 which serves as a deflecting flange.

A target forming member 94 is also adapted to slideably engage in the opening formed in the member 92 with sufficient clearance around the member 94 to permit a bullet striking such space to pass between the members 92 and 94 rearwardly so that it will engage the deflecting flange 95 formed on the member 94 and which overlies the opening formed in the member 92. As shown in Figs. 11 and 12, the member 92 is carried by a pair of spaced arms 96 and the member 94 is carried by a pair of spaced arms 97, these arms being swingably mounted on the shaft 98 which is journalled in spaced supporting arms or bearings 99 which project inwardly from the member 88. The springs 101 mounted on the shaft 98 serve to normally retain the arms 96 and 97 swung to such a position that the members 92 and 94 will engage as shown in Fig. 11. The arrangement of the tube 55 and the plate 88 is such that the member 94 will be positioned centrally of the inner end of the tube 55 thus mounting a target adjacent the inner end of the tube 55.

Projecting outwardly from one of the arms 97, 45 is a switch closing arm 102 carrying on its outer end a block 103 of insulating material such as rubber or the like, which is adapted to engage one end of the spring arm 104 which is fixedly attached at its opposite end to the lug 105 projecting inwardly from the plate 89. This spring arm 104 carries a contact 106 adapted to engage a contact 107 mounted on the spring arm 108 which is also attached to the lug 105. An electric wire 109 is connected to the spring plate 104 and a wire 110 connects to the spring arm 108. The plate 89 is formed of insulating material.

A switch closing arm 111 is carried by one of the arms 96 and provided on its outer end with a block 112 of insulating material such as rubber 60 or the like and which is adapted to engage one end of the spring arm 113, the opposite end of which is attached to the lug 115 projecting inwardly from the plate 89. This spring arm 113 carries a contact 114 attached to engage the contact 118 carried by the spring arm 117 which is also attached to the lug 115. A wire 116 connects to the arm 113 and a wire 119 connects to the arm 117.

Formed centrally in the member 94 is an opening 120 which corresponds to the "bull's-eye" of a target. The space between the member 94 and the member 92 and the space between the member 92 and the member 88 serving as indicating lines for defining the various areas on the 70 75

target. Thus, it is positioned concentrically of the tube 55 and visible through the tube 49 a structure simulating in all respects the usual target.

5 Secured to and depending from the plate 89, is the trough-shaped plate 121 having the side walls 123 and the base 122. Mounted on this base is a trough-shaped bracket comprising the base 124, the end wall 125 and the side walls 126. 10 Swingably mounted on a shaft 127 projected through the side walls 126 is a switch closing plate 128 normally held rocked forwardly by the spring 129 which engages in the cup-shaped recess 130 formed in the base 124 adjacent the 15 upper end thereof. Projecting rearwardly from the upper end of the plate 128 is a contact boss or leg 131 which engages one end of the spring arm 132 which carries the contact 134, adapted to engage the contact 135 carried by the arm 136. 20 These arms 132 and 136 are mounted on the lug 137 which projects inwardly from the plate 89. A wire 138 connects to the arm 136 and a wire 139 connects to the arm 132. Mounted on the base 122 of the bracket, is a socket 140 for reception of a light bulb.

The construction of these parts is such that, upon a rocking rearwardly of the member 92, the arm 111 would effect a flexing of the spring arm 113 so that the contacts 114 and 118 would engage and thus a circuit, to be hereinafter described, would be closed. Similarly, a rearward swinging of the member 94 would effect, through the arm 102, a closing of a circuit by bringing the contacts 106 and 107 together. When the 35 person using the gun 50 shoots so as to strike the member 92 on its face or so as to pass through the space surrounding the member 92 and strike the flange 93, the member 92 would be forced rearwardly so that the arm 111 would effect a closing of a circuit by bringing the contacts 114 and 118 together. Similarly, should the member 94 be struck on its face, or should the flange 95 be struck by a bullet, the arm 97 would 40 rock to force the contacts 106 and 107 together. Should the bullet pass directly through the opening 120, it would then impact against the plate 128 which is positioned rearwardly of and in alignment with the opening 120. This impact of the bullet would cause the plate 128 to rock rearwardly so as to bring the contacts 134 and 135 together. In normal operation, the motor 84 would be operating so that the plate 88 would be oscillating across the end of the tube 55 but never passing out of the area defined by the end 45 of the tube 55. At the same time, the lights mounted in the sockets 61, 69, 72 and 140 would be lit so as to well illuminate the target and clearly define the opening 120, the space surrounding the member 94, and the space surrounding the member 92.

60 Mounted on and projecting outwardly from the front wall, as shown in Fig. 6, is a guide sleeve 141 through which is slideably projected a plunger 143 adapted to receive a coin deposited in the opening 142 and carry the same inwardly for depositing it in the coin chute 144. This type of control is one which is well known and its detail of structure is not illustrated as it forms no part, by itself, of the present invention. The construction is such that, the plunger 143 cannot be forced inwardly unless a coin is positioned in the opening 142. Projecting upwardly from the inner end of the plunger 143 is a stud 144 which engages in a slot 145 formed in the switch arm 146 which 65 extends into the switch box 147 and serves to

operate the switch contained therein. The cable 148 serves to conduct the wire into the switch box 147. A spring 149 fastened at one end to the stationary sleeve 141, and at its opposite end to the inner end of the plunger 143, serves to normally retain the plunger 143 pressed outwardly.

75 When the plunger 143 is pressed inwardly, it will strike at its inner end against the up-turned end 150 of the crank, the downwardly-turned end 151 of which is journaled in an opening formed in the supporting plate 152 which is mounted within the housing. Consequently, an inwardly pressing of the plunger 143 serves to rock the crank on its pivot. This crank portion 151 projects through and is fixedly attached to a link 153. 10 To one end of this link 153 is pivotally mounted the dog 155 by the pin 154. The spring 153' serves to retain the dog 155 rocked into operative position so as to normally retain it in contact with the teeth 172. A spring 158 is attached at one 15 end to the link 153 and at its opposite end to the post 159 projecting upwardly from the supporting plate 152 so as to normally retain the link 153 moved into the position shown in Fig. 6. When in this position, the link 153 will engage the stop 20 post 157 which projects upwardly from the supporting plate 152. Pivotally connected by the pin 161 to one end of the link 153 is one end of a bar 160 which is slideably projected through the guide strap 162. Pivoted on the end of this bar 30 160, intermediate its ends by means of the pin 164, is a rocker arm 163 carrying the outwardly projecting stud 165 adapted to engage the control arm 166 of a time switch 167 leading from which are the wires 169 and 170. The spring 35 171 serves to normally prevent a rocking of the member 163 in one direction, one end of this spring 171 being attached to the end of the member 163 and the other end of the spring 171 being attached to the bar 160. The teeth 172 are 40 formed on the magazine base 173 which is rotatably positioned on the supporting plate 152, as shown in Fig. 7 and in Fig. 8. A shaft 174 projects centrally through the base 173 and this base 173 is adapted to rotate about the axis of 45 the shaft 174. It will be noted, that the base 173 is cup-shaped and formed in the side walls of this cup-shaped base are axially directed passages 175. A peripheral slot 176 is formed on the side wall of this cup-shaped base so as to open into the passages 175. Lying in this slot 176 is a wire 177, one end of which is attached to the post 178 and the other end of which is coiled into a spring coil 177' and attached to the post 159 so that the wire 177 is retained in position to extend into and lie across a number of passages 175 as clearly appears in Fig. 6. Pressed into the upper end of each of these passages 175 is one end of a tube 179, the upper ends 180 of which are crimped inwardly. The shaft 174 is projected centrally 50 through the spacing disc 181 which is provided with a plurality of peripheral recesses 181', in each of which engages one of the tubes 179 as clearly appears in Fig. 9. Consequently, the disc 181 serves to retain the tubes extended in parallel 55 relation upwardly from the base 173.

The shaft 174 also projects centrally through the cover 182 which engages the upper ends of the tubes 179 and which is formed cup-shaped to provide the embracing flange 183 which snugly 60 embraces the row of tubes. A nut 184 is threaded on the shaft 174 to retain the cover 183 pressed tightly against the upper ends of the tubes 179.

70 Formed in the supporting base 152 in alignment with the row of tubes 179, is an opening 185 75

communicating with a discharge chute 186 leading to a discharge cup 187 mounted on and extended outwardly of the front wall 39. The construction is such that, if the base 173 is rotated about the axis of the shaft 174, the passages 175 are successively brought into register with the opening 185. Projecting upwardly from the cover 182 are studs 188 spaced apart circumferentially around the cover a distance equivalent to the distance of the row of tubes 179. Projecting inwardly from the front wall is a supporting bracket 192 carrying the pin 191 which projects through the dog 190, intermediate its ends, and serves to pivotally mount the same. One end of this dog lies in the path of the studs 188 and the other end is attached to a lever 194 which is fixedly mounted upon a shaft 195 projecting into the housing 196 in which a counting mechanism is mounted and visible through its front end 197 which is positioned exterior of the front wall 39. The particular structure of the counting mechanism is not shown, as it may be of any well-known mechanical type. A spring 193 is attached at one end to the dog 190 and at its opposite end to the bracket 192 to normally retain the dog 190 swung to a position so that it will be entered successively by the studs 188 as the cover 182 is rotated. The tubes 179 are adapted for reception of bullets 198, these bullets being mounted in the tubes as shown in Fig. 8.

The mechanism illustrated in Figs. 6, 7 and 8 is such that, upon an inward pressing of the plunger 143, the crank will be rocked on its portion 159 to effect a rocking of the link 153 clockwise, in the form shown in Fig. 1, so as to rotate the base 173 a distance equal to the one of the teeth 172. These teeth are spaced apart to correspond with the spacing between the tubes 179. At the same time, the bar 160 will serve through the switch arm 166 and close the time switch 167. As shown in Fig. 8, the wire 177 serves to prevent the downward passage of the bullets in the tubes from above so that as the base 173 is rotated to bring one of the passages 175 into register with the opening 185, only those bullets positioned below the wire 177 will pass into the discharge chute 186 as clearly appears in Fig. 8.

In loading the tubes, they are removed and the bullets are inserted from the lower end thereof. The crimped upper ends 180 preventing the passage of bullets therethrough. A pin may then be inserted into the opening 199 formed in the tubes 179 adjacent their opposite end, to prevent undue dislodgement of the bullets from the tubes and thus facilitating their being carried from the place of loading to the structure.

In operation, when the plunger 143 is pressed inwardly it will close the time switch 167 which is interposed in the feed line 202 as shown in Fig. 60 14. This feed line cooperates with the feed line 201. Upon the closing of the time switch 167, the circuit to the motor 84 and to each of the lights 69, 67, 72 and 140 will be closed. At the same time, the plunger will serve to operate the switch in the switch housing 147 and this switch 147A is illustrated in the diagrammatic view as being interposed in the line 203 leading off of the line 201. This line 203 connects to one end of the magnetic coils 204, 206 and 207, connecting directly to one end of the coil 204 and connecting to the coils 206 and 207 by the wires 205 and 208 respectively. The opposite ends of these coils 204, 206 and 207 are connected to the wire 202 through the wires 209, 210 and 211. Consequently, upon an inward pressing of the

plunger 143, each of the coils 204, 206 and 207 are energized at the same time that the motor 84 is set into operation and the light bulbs referred to are lit. Each of these coils 204, 206 and 207 is provided with a core 212 pivotally connected at its outer end to a dog 213 which is pivoted at one end and adapted at the opposite end for engaging the ratchet teeth 214 formed on the rotatable discs 215, 216 and 217, which may be made from suitable insulating material. A spring 10 218 serves to retain the dog 213 in engagement with the ratchet teeth 214. Each of these discs 215, 216 and 217 is rotatably mounted on a stationary shaft 219 to which is attached one end of the helical spring 220, the opposite end thereof being attached to a stud 221 projecting outwardly from the face of the disc. The construction is such that, upon a rotation of the disc in a clockwise direction, in the drawing illustrated in Fig. 14, the spring will be wound to increase its tension and the teeth 214 will ride over the dog which will snap into engagement with each successive tooth and prevent reverse rotation of the discs 215, 216, and 217 as the case may be. Each of these discs is provided with arcuate metallic stripping 222 contacting with each of which is a brush contact member 223 connected by a suitable wire 224 to the feed line and its connecting wires to the feed line 202. The light bulbs 60', 61' and 62' positioned in the compartments 60, 30 61, and 62 are each connected through the wiring 225 to the feed line 201. Each of these light bulbs is also connected through the wire 226 to a contact brush 227 which engages the periphery of the discs 215, 216 and 217 as the case may be, 35 and which is adapted to contact the arcuate contact strips 222 upon the clockwise rotation of the disc a predetermined distance. As the discs are rotated in a clockwise direction, the light bulbs in each compartment will be successively lighted. 40 For instance, if the disc 215 rotates in a clockwise direction, the three light bulbs, which constitute the group of light bulbs 60, would be successively lighted. A similar action would take place at each of the discs 216 and 217.

These discs and their associated parts, are 45 mounted in the housing 73.

At each of the discs there is provided an actuating mechanism to effect a clockwise rotation of the disc. This mechanism is the same at each of the discs so that a description of one will suffice for all. For operating the disc 215, I provide a magnetic coil 228 one end of which is connected by the wire 139 to the spring arm 132 so that when the contacts 134 and 135 are engaged with each other, one side of the coil 228 will be connected to the feed line 202, the other side of this coil 228 is connected through the wire 230 and 231 to the feed line 201. Associated with the disc 216, is a magnetic coil 232 one end of which is connected by the wire 119 to the spring arm 117 so that when the contacts 114 and 118 are engaged, one end of the magnetic coil 232 will be connected through these contacts 118 and 114 and the wires 116, 109 and 138 to the feed line 202. 60 The opposite end of the coil 232 is connected through the wire 233 and the wire 231 to the feed line 201. Associated with the disc 217 is a magnetic coil 234 one end of which is connected by the wire 110 to the spring arm 108 so that when the contacts 106 and 107 are engaged, one side of the coil 234 will be connected through the wire 109 and 138 to the feed line 202. The opposite end of the coil 234 is connected by the wire 231 to the feed line 201. 70

The operating mechanism associated with each of the coils 228, 232 and 234 is the same in each of these coils and is provided with a slideable core 235 having a slot 236 formed therein in which engages a pin 237 projecting outwardly from the end of the pivotally mounted arm 238. Mounted intermediate its ends pivotally on the arm 238 intermediate its ends, is a dog 240 to one end of which is attached a spring 241 to normally maintain this dog 240 rocked downwardly against the stop pin 242. The construction is such that, upon energizing of either of these coils, the core 235 will be drawn toward the left of the drawing so as to rock the arm 238 and force the end of the dog 240 into engagement with one of the ratchet teeth 243 and rotate the disc clockwise a distance equal to the space between a pair of ratchet teeth, the ratchet teeth 214 riding over the dog 213. The dog 213 serves to prevent reverse rotation. In the form shown in Fig. 14, each of the discs is rotated counterclockwise the limit of its movement. A stop pin 244 engaging the endmost tooth 243 to prevent further reverse rotation. When the plunger is forced inwardly and the switch 174A closed, each of the coils 204, 206 and 207 being energized, will cause the core 212 to be moved to the left of the drawing so as to disengage the dog 213 from the ratchet teeth 214 and permit a reverse rotation of the discs if they have previously been moved clockwise by the actuation of the dog 240. When the plunger has been pressed inwardly and the time switch 167 set, the target will be oscillating and illuminated and all of the discs 215, 216 and 217 will be returned to neutral position. When the operator shoots and makes a bull's-eye, by directing the bullet through the passage 120 so as to rock the plate 128 to bring the contacts 134 and 135 into engagement with each other, the coil 228 would be energized and the disc 215 would be moved clockwise sufficiently to bring the arcuate metallic strips 222 into engagement with one of the brushes 227 so as to close the circuit to one of the light bulbs in the group 60'. I have shown three light bulbs in each group as it is intended that the machine shall operate by depositing three bullets in the discharge cup at each operation. Should the operator again strike a bull's-eye, the disc 215 would be moved to light the second bulb in the group 60', the dog 213 retaining the disc 215 moved to this position. Should another shot also make a bull's-eye, the disc 215 would be rotated clockwise to a distance to close the circuit to the other bulb in the group 60'. The time switch is so set as to allow ample time to shoot three shots but still limiting it to such an extent as to require quick action on the part of the shooter and when the time expires and the time switch 167 opens and the circuit to the light bulb 69, 67, 72 and 140 as well as the motor 84 would be broken at the next operation. When the plunger 143 is pressed inwardly the switch 147A would be closed to energize the coil 207 so as to release the dog 213 from engagement with the teeth 214 and permit the reverse rotation of the disc 215 to neutral position as shown in Fig. 14. This switch 147A remains closed only while the plunger is pressed inwardly and upon release of inward pressure the spring 149 would pull the plunger 143 outwardly so that the switch 147A is normally open.

The discs 216 and 217 operate in the same manner as does the disc 215. When the bullet strikes the member 94 so as to rock the arm 97 and move the contacts 106 and 107 into engagement, the coil 234 would be energized to move the

disc clockwise a sufficient distance for lighting one of the bulbs in the group 62'. Similarly, when the member 92 is struck by a bullet so as to effect a rocking of the arms 96 and force the contact 118 and 114 into engagement, the coil 232 would be energized to rotate the disc 216 clockwise a distance sufficient for lighting one of the bulbs in the group 61'.

Thus, the bulbs in the groups 60', 61' and 62' serve as a means for indicating to the shooter the results of his shooting. It is believed apparent from the description already given that as the plunger 143 is pressed inwardly, in addition to setting the mechanism into operation as already described, the feeding mechanism will be moved to a position to discharge a predetermined number of bullets 198. The operator then will load the gun while the muzzle is still retained in the tube 49 and proceed to shoot while the lights illuminating the target are turned on. The fan will operate to maintain the mechanism free from smoke and obnoxious gases. It is thus provided a construction in which target practice may be safely carried on, leaving the individual shooter in full control of the mechanism. By observing the counter 196, the operator will be able to tell the number of bullets which have been discharged from the tubes 179, as this counting mechanism will be operated every eleventh movement of the plunger 143. It is obvious of course that the counter may be regulated to indicate other than every eleventh operation, but this mechanism is provided so that there will be clearly indicated at all times, the number of bullets which have been fed out of the tubes 179.

In Fig. 15 and Fig. 16, I have shown a slightly modified form of the invention in which the motor 84 is supported by the bracket 245 and the lug 246 which is pivoted to the end of the bracket 245. The lug projects from the housing of the motor 84. In place of the gear 81, I have substituted a pulley 81' around which passes a belt 247. This belt also passes around a pulley 248 rotatably mounted on the shaft 249. This shaft 249 is journaled in bars formed on the arms 250 and 251 which project inwardly from the tube 44 fixedly. The pulley 248 is fixed to the hub 252 projecting centrally outwardly from the circular disc 253 which is rotatably mounted on the shaft 249. Through this disc 253 is formed a pair of circumferential concentric rows of passages 120'. Behind the disc 253 is positioned a plate 128' corresponding to and mounted in the same manner as is the plate 128. The boss 131' is adapted, upon a rearward rocking of the plate 128', to force the contact 134' into engagement with the contacts 134' and 135' corresponding to the contacts 134 and 135 and being similarly connected. The contact 134' is mounted on the spring arm 132' which is mounted on the horizontally turned extension 254 formed on the upper end of the standard 255. The contact 135' is mounted on the enlarged portion 256 of the standard 255. These parts all function to the same end and purpose as do the parts associated with and operated by the plate 128.

It will be noted, that in this form, shown in Fig. 15 and Fig. 16, the parts 92 and 94 are dispensed with, together with the circuit closing parts operated by the arms 96 and 97 so that the housing which is divided into the compartments 60, 61, and 62 would be provided with only one set of compartments and but one of the discs, shown in Fig. 14, would be utilized. It will be noted, however, that the disc 253 would be rotated

when the counter is set into operation so that the target would comprise a rotating disc instead of an oscillating one.

In both forms of the invention shown, the members 49, 52 and 55 are used and these members together may be considered a tunnel at the end of which the target is located. The target is located beyond the end of the tunnel a sufficient distance to permit the bullets impacted 10 against the members 88, 92 and 94 to drop downwardly in the space between the end of the tunnel and the target.

With a device constructed in this manner, it is believed obvious that the variations enumerated 15 are obtained and a durable, practical, operative structure provided.

While I have illustrated and described the preferred form of construction, I do not wish to limit myself to the precise details of structure 20 shown, but desire to avail myself of such variations and modifications as may come within the scope of the appended claims.

What I claim as new is:

1. In a shooting range of the class described, 25 a bullet discharging magazine; means for operating said magazine for discharging a predetermined number of bullets therefrom; a shooting tunnel; means for illuminating said tunnel; a movable target positioned at the end of said tunnel; means for moving said target; a timing control means for controlling said moving means and said illuminating means; and means operable upon the operation of said magazine for instituting the operation of said timing control 30 means.
2. In a shooting range, a cabinet having a shooting tunnel, a gun movably mounted at one end of said cabinet, a movable target mounted at the other end of said cabinet, means for moving the target and means for illuminating said target, a bullet discharging magazine, means for operating said magazine for discharging a plu- 35

rality of bullets therefrom, and a control mechanism for all of said means whereby the illumination and initiation of movement of said target is synchronized with discharge of bullets from said magazine, and timing means on said control means whereby the illumination and movement of said target continues for a predetermined period of time. 5

3. In a shooting range, a cabinet having a shooting tunnel, a gun movably mounted at one end of said cabinet, a movable target mounted at the other end of said cabinet, means for moving the target and means for illuminating said target, a bullet discharging magazine, means for operating said magazine for discharging a plurality of bullets therefrom, and a coin-actuated control mechanism for all of said means whereby the illumination and initiation of movement of said target is synchronized with discharge of bullets from said magazine, and timing means on 20 said coin-actuated control means whereby the illumination and movement of said target continues for a predetermined period of time after insertion of a coin in said control mechanism. 15

4. In a shooting range, a cabinet having a 25 shooting tunnel, a normally unloaded gun mounted at one end of said cabinet, a movable target mounted at the other end of said cabinet, means for moving the target and means for illuminating the target, a means comprising a bullet discharging magazine for making a predetermined number of bullets available to an operator whereby he may manually load said gun, and a control mechanism for all of said means whereby the illumination and initiation of movement of said 30 target is synchronized with discharge of said bullets from said magazine, and timing means on said control means whereby illumination and movement of said target continues for a predetermined period of time after bullets have be- 40 come available to the operator. 35

EDWARD A. GORNEY.
